UNITED STATES PATENT OFFICE.

FRANK N. KROESEN, OF INDIANAPOLIS, INDIANA.

ENVELOPE OPENER.

Application filed July 24, 1924. Serial No. 728,012.

To all whom it may concern:

Be it known that I, FRANK N. KROESEN, a citizen of the United States, residing at Indianapolis, in the county of Marion and State of Indiana, have invented certain new and useful Improvements in an Envelope Opener, of which the following is a specification.

This invention relates to new and useful improvements in envelope openers and has for its principal object to provide a simple and efficient device for slitting one of the edges of a sealed envelope in order to remove the contents thereof without tearing the contents thereof as frequently happens in opening a sealed envelope by hand.

A further object of the invention is to provide an envelope opener of the above mentioned character, wherein means is provided for clamping the envelope so that the same will be maintained in proper position while one edge thereof is being slit, additional means being provided for releasing the clamping means after the envelope has been slit.

A further object of the invention is to provide an envelope opener of the above mentioned character, which is of such a construction as to enable a person to open letters or the like expeditiously and in such a manner as not to sever any portion of the contents of the sealed envelope.

A further object of the invention is to provide an envelope opener of the above mentioned character, which is simple in construction, inexpensive, strong and durable and furthermore adapted for the purposes for which it is designated.

Other objects and advantages of this invention will become apparent during the course of the following description.

In the accompanying drawings forming a part of this specification and in which like numerals designate like parts throughout the same:

Figure 1 is a top plan view of my improved envelope opener.

Figure 2 is an end elevation thereof.

Figure 3 is a transverse section taken approximately on line 3—3 of Figure 1.

Figure 4 is a bottom plan view of the carriage.

Figure 5 is a vertical sectional view of the carriage showing the manner in which the rotary cutter is mounted thereon, and

Figure 6 is a detail perspective view of the stop plate.

In the drawing wherein for the purpose of illustration is shown the preferred embodiment of my invention, the numeral 1 designates generally the base of my improved envelope opener and the same has its side and end flanges depending therefrom so that the base will be spaced from a table or the like upon which the same is placed. The base is preferably constructed of pressed metal although any other suitable material may be substituted therefor and I do not wish to limit myself to the particular kind of material to be used. The base 1 is provided with a longitudinally extending slot 2 adjacent the forward longitudinal edge of the base and the purpose thereof will hereinafter be more fully described. Secured on the base 1 and extending longitudinally thereon adjacent the forward longitudinal edge thereof is the stationary cutter blade and the cutting edge 4 thereof is disposed directly adjacent one of the longitudinal edges of the slot 2 in the manner more clearly illustrated in Figure 3 of the drawings. The securing means for the stationary cutter blade 3 is shown at 5.

Pivottally supported between the upstanding brackets 6 and 7 respectively mounted on the base 1 adjacent the ends of the stationary cutter blade 3 is the envelope clamping plate 8. The clamping plate 8 is disposed adjacent the cutting edge 4 and the slot 2 and the purpose thereof will also hereinafter be more fully described. One of the ends of the clamping plate 8 is provided with an extension 9 and extending through the outer end of the extension is the headed pin or bolt 10, the same extending through a suitable opening provided in the base 1. A nut 11 is threaded on the lower end of the bolt and interposed between the nut and the bottom of the base is the coil spring 12, the same encircling the lower portion of the bolt in the manner clearly illustrated in Figure 3 of the drawings. The purpose of the construction is to provide a means whereby the clamping plate is normally held in engagement with the stationary cutter blade 3.

Adapted for slidable movement on the base 1 is the carriage designated generally by the numeral 13. The carriage has an extension 14 provided on the lower portion

thereof which operates within a suitable slot 15 provided in the base 1 and which extends longitudinally adjacent the intermediate portion of the base. The longitudinal edges of the slot 15 on the under side of the base 1 have the longitudinally extending ribs 16 and 17 formed thereon and the purpose thereof is to provide a means for cooperation with the upwardly disposed ends 18 and 19 respectively. The plate 20 which is secured to the bottom of the extension 14 by any suitable fastening means such as is illustrated at 21. This construction enables the carriage to be slidably supported on the base and against accidental disengagement therefrom and from the slot 15.

The carriage 13 is provided at its forward end with the enlarged head 22 and the central portion of the carriage has extending upwardly therefrom the handle portion 23. The carriage is further provided with a longitudinally extending recess which terminates at a point adjacent the rear end thereof and the same is illustrated at 24 in the drawings. Supported in the recess 24 is the shaft 25, the forward end of which extends beyond the forward face of the carriage and rotatably supports thereon the rotary cutter 26. The inner end of the shaft 25 is reduced as illustrated at 27 and encircling the reduced portion of the shaft 25 is the coil spring 28. One end of the coil spring abuts the shoulder formed on the shaft 25 while the opposite end of the spring engages the inner wall of the recess 24 in the manner more clearly illustrated in Figure 5 of the drawings.

The lower portion of the forward enlarged head 22 of the carriage 13 is cut away as illustrated at 29 and secured on the cut away portion 29 and extending laterally from the carriage is the finger 30, the outwardly projecting end of which is reduced and slightly beveled and the purpose thereof will hereinafter be more fully described. Extending over the forward end of the carriage and removably supported on the enlarged head thereof is the guard 31, the same acting as a protector for the rotary cutter blade 26, it being also understood that the guard 31 is cut away at its lower portion to cooperate with the cut away lower portion of the enlarged head of the carriage. The rotary cutter 26 is adapted to operate in the slot 2 and cooperates with the cutting edge 4 of the stationary cutter blade 3 when the device is in use as will be hereinafter more fully described.

Secured to the under side of the base 1 adjacent the slot 2 and extending longitudinally thereon is the plate 32 and the same has its forward edge bent upwardly to provide a stop flange 33 and this flange extends upwardly within the slot 2 and directly be-

hind the rotary cutter 26 in the manner clearly illustrated in Figure 3.

The use of my improved envelope opener may be briefly stated as follows:—A sealed letter is inserted beneath the clamping plate 8 so that the edge to be slit engages the stop flange 33. The carriage being positioned at one end of the slot 15 is then moved longitudinally on the base by means of the handle portion 23 and as the carriage moves along 75 on the base, the rotary knife or cutter blade 26 cooperating with the stationary cutter blade 3 will slit the edge of the envelope in a uniform manner, it being understood of course that the clamping plate 8 is normally 80 under the tension of the coil spring 12 holds the envelope in proper position on the base in order to slit one of the edges thereof without cutting or otherwise severing the contents of the envelope.

When the carriage has traveled the full length of the slot 15, the finger 30 carried by the cut away portion 29 on the forward end of the carriage will have its beveled free end engaging the extension 9, causing the latter 90 to move upwardly against the tension of the coil spring and releasing the clamping plate 8 from engagement with the envelope whereby the latter may be readily and easily removed after the same has had one of its 95 edges slit. When the finger is disengaged from the projection 9 or extension formed on one end of the clamping plate, the latter will resume its normal position and will be in a position ready to receive another envelope which is to have one of its edges slit.

The provision of an envelope opener of the above mentioned character, will enable considerable time and labor to be saved in opening sealed letters and furthermore the device will at all times be positive and efficient in its operation. Furthermore the construction of my improved envelope opener is such as to enable the several parts to be readily disassembled whenever it becomes 110 necessary.

While I have shown the preferred embodiment of my invention, it is to be understood that various changes in the size, shape and arrangement of parts may be resorted to without departing from the spirit of the invention and the scope of the appended claim.

Having thus described the invention, what I claim is:—

An envelope opener comprising a base 120 having a longitudinal opening therein, a stationary cutter blade on said base, the cutting edge thereof being disposed adjacent said opening, a clamping plate mounted on said base and adapted to hold an envelope in position on the base, a stop for the edge of the envelope to be slit, a carriage slidable on the base, and a rotary cutter carried by the carriage, said rotary cutter disposed in said opening and cooperating with the cutting 130

edge of the stationary cutter blade in slitting the edge of an envelope, means for releasing the clamping plate from engagement with the envelope, said means comprising an extension formed on one end of the clamping plate, means associated with the extension for normally holding the clamping plate un-

der tension, and a finger projecting laterally from the carriage and adapted to engage the extension after the edge of the envelope has 10 been slit and the carriage has traveled the full length of the opening.

In testimony whereof I affix my signature.

FRANK N. KROESEN.
